RIBBON MECHANISM FOR RECORDING APPARATUS

Alfred Ruttiman, Gardner, Mass., assignor to Simplex Time Recorder Co., Gardner, Mass., a corporation of Massachusetts

Application November 12, 1936, Serial No. 110,481

12 Claims. (Cl. 197—161)

This invention relates to apparatus for making records by stamping an impression through an inked ribbon. While capable of general application, the invention is particularly designed 5 for use in connection with time stamp apparatus and is so shown in this application.

It is the general object of my invention to provide improved mechanism for feeding the ribbon at each operation of the time stamp, and particularly 10 for automatically reversing the ribbon feed when the travel of the ribbon in a given direction is nearly completed.

More specifically, I provide feeding and reversing mechanisms which are both operated directly 15 from the impression or hammer mechanism of the time stamp, and I so construct the reversing mechanism that no extra strain is placed on the ribbon at the time of reversal.

My invention further relates to arrangements 20 and combinations of parts which will be herein-after described and more particularly pointed out in the appended claims.

A preferred form of the invention and certain 25 modifications thereof are shown in the drawings, in which

Fig. 1 is a side elevation of a time stamp, partly in section and having my improved ribbon mechanism supplied thereto;

Fig. 2 is a plan view of the ribbon mechanism 30 with the casing or cover removed;

Fig. 3 is a partial end elevation, looking in the direction of the arrow 3 in Fig. 2;

Fig. 4 is a side elevation of certain parts, looking in the direction of the arrow 4 in Fig. 2;

Fig. 5 is a side elevation of an operating lever;

Fig. 6 is a plan view thereof, looking in the direction of the arrow 6 in Fig. 5;

Fig. 7 is a sectional front elevation, taken along the line 7—7 in Fig. 4;

Fig. 8 is a similar view showing a modified friction device;

Fig. 9 is a plan view of certain feed reversing devices;

Fig. 10 is a side elevation thereof, looking in the direction of the arrow 10 in Fig. 9;

Fig. 11 is a view similar to Fig. 10 but showing additional parts and indicating the method of reversal;

Fig. 12 is a partial sectional side elevation showing modified operating connections;

Fig. 13 is a sectional side elevation of a modified form of ribbon mechanism; and

Fig. 14 is a sectional side elevation of an additional modification.

55 Referring particularly to Figs. 1 to 11, I have

shown a preferred form of my invention embodied in a time stamp comprising a base 20 (Fig. 1) in which an impression plate or hammer 21 is secured to the upper end of a solenoid plunger 22 movable vertically by a solenoid coil 23. 5

The machine is manually set in operation by pressing rearward a push plate 24 pivoted at 25 near the front of the machine. The push plate 24 carries a stud 26 which engages a lever 27 having a latch 28 pivoted thereto near its upper end. 10 A shoulder 29 on the latch engages a plate 30 secured to the upper end of a spring arm 31 but insulately therefrom.

The arm 31 is connected to one line wire L and is provided with a contact 32 which engages a 15 fixed contact 33 when the spring arm 31 is pushed rearward. The contact 33 is connected through a wire 34 to one end of the solenoid coil 23, the other end being connected to a second line wire L'. When the push plate 24 is moved rearward, 20 the circuit is completed through the solenoid and the impression plate or hammer 21 is moved forcibly upward to make the impression.

As the hammer moves upward, an offset plate 35 carried thereby engages the end 36 of the latch 28 25 and releases the spring arm 31, thus breaking the circuit.

The type wheels or other devices from which the 30 impression is made are mounted in an upper casting portion 37, pivoted at 38 to the base 20 and normally secured in fixed operative position by fastening devices not shown.

The parts thus far described are of the usual 35 commercial construction and in themselves form no part of my present invention.

My improved ribbon feed mechanism is mounted on brackets 40 and 41 (Figs. 1 and 4) secured to the top of the base portion 20. Front and rear ribbon spools S and S' are pivoted in openings in the rear bracket 41, and the front ends 40 of the spools are inserted in sockets 42 in driving studs 43 and have a tongue and slot connection therewith, as clearly indicated in Fig. 7. Each stud 43 is rotatable in a bearing bushing 44 fixed in a bracket 40, and each stud 43 has a ratchet 45 wheel 45 or 46 secured thereto by its hub 47.

Each bushing 44 is recessed to receive a spring 48 which causes the adjacent ends of the bushing 44 and hub 47 to frictionally engage, thus retarding backward movement of a ribbon spool after a 50 feeding advance movement thereof.

In Fig. 8 I have shown a modified construction in which an annular coil spring 50 is mounted in a V-shaped groove between adjacent conical surfaces, one of said surfaces being formed on the end 55

of a fixed bushing 51 and the other on the adjacent end of a sleeve 52 fixed to the end of the stud 53 on which the ratchet wheel 45 and its hub 41 are mounted. This spring 50 also exerts a 5 frictional or retarding action and effects the same result as the spring 48.

A flat spring 55 (Fig. 2) engages the rear ends of the spools S and S' and forces the forward ends of the spools firmly into the slotted sockets. 10 I will now describe the mechanism for intermittently and alternately advancing the ribbon spools.

For this purpose I provide an operating lever 60 (Figs. 1 and 5) pivoted at 61 to the bracket 40 and limited in its downward movement by engagement of a recessed portion 62 (Fig. 5) with a reduced portion 63 (Fig. 7) of the bushing 44. 15

The lever 60 is also provided with an offset flange 64 (Fig. 6) which engages a recessed portion 65 (Fig. 4) of the bracket 40 and thus limits 20 upward movement of the lever. A spring 66 assisted by gravity moves the lever 60 downward.

Feed pawls 70 and 71 (Fig. 1) are pivoted at 72 and 73 to the lever 60 and the upper ends of 25 the feed pawls are yieldingly connected by a tension spring 74. The lower ends of the pawls 70 and 71 alternately engage the ratchet wheels 45 and 46 previously described.

A lock lever 75 is pivoted at 76 on the lever 60 30 and is provided with offset or locking portions 77 and 78. The feed pawls 70 and 71 are provided with recessed portions 80 and 81 to alternately receive the offset locking portions 77 and 78.

When the locking lever 75 is in the position shown in Fig. 1, the portion 78 is seated in the recessed portion 81 of the feed pawl 71, thus holding 35 the pawl 71 inoperative, but the offset portion 77 is raised above the feed pawl 70, thus releasing the pawl 70 for feeding its associated ratchet wheel 45.

When the locking lever 75 is moved anti-clockwise to its alternative locking position, the pawl 70 is rendered operative and the pawl 71 is released to feed the ratchet wheel 46. 45

I will now describe my improved means for automatically shifting the locking lever 75 and thus reversing the ribbon feed.

I provide a crank shaft or lever 82 (Fig. 9) 50 pivoted in the front and rear brackets 40 and 41 and having the crank portion 83 thereof positioned for engagement by the roll of ribbon R wound on the spool S', as clearly shown in Fig. 11. A hook arm 84 is secured to the front end of the crank lever 82. As the roll of ribbon on the spool S' increases in diameter, the hooked upper end of the arm 84 is moved to the position shown in Fig. 11, in which it overlies the offset portion 77 of the locking arm 75.

On the next upward movement of the operating lever 60, the hook arm 84 gives the locking lever 85 a relative anti-clockwise movement and causes 60 the offset portion 77 to enter the depressed portion 80 of the lever 70. This holds the lever 70 65 inoperative, while at the same time releasing the lever 71 to feed the ribbon in the opposite direction.

A second crank lever 86 is similarly pivoted in the brackets 40 and 41 and is provided with a 70 crank portion 87 to engage the ribbon R when wound on the spool S, as indicated in Fig. 10.

The crank lever 86 has a hook arm 88 secured to its forward end and the two hook arms are yieldingly connected by a tension spring 89. 75 When the spool S is filled as indicated in Fig. 10,

the hook end of the arm 88 will overlie the offset portion 78 of the locking lever 75 and will cause the same to swing the feed pawl 71 relatively downward to the position shown in Fig. 1 as the operating lever 60 rises. The lever 75 also locks the pawl 71 in inoperative position, at the same time releasing the pawl 70. 5

The operating lever 60 is directly engaged and raised against gravity and against the tension of the spring 66 by an extension 90 at one side 10 of the platen or hammer 21, so that the power for operating the ribbon feed comes indirectly from the solenoid coil 23. It will also be noted that the shifting of the locking lever 75 and reversal of feed is directly effected by the upward 15 blow of the hammer extension 90, transmitted through the operating lever 60.

I thus provide for automatically reversing the ribbon travel when a ribbon roll of predetermined size has been formed on one or the other 20 of the spools S and S', and I effect this reversal on indication of enlarged roll diameter, as given by the crank levers 82 or 86. I entirely avoid the shifting of any parts by the pull of the ribbon, 25 communicated through a seam or enlargement therein, as has been heretofore commonly practiced.

My improved feeding apparatus is simple and effective in operation and is independent in its 30 operation of the time or other mechanism for driving the type wheels.

While I prefer to actuate the lever 60 by a direct blow from the hammer extension 90, it is sometimes desirable to take the power direct from the plunger 22, in which case the construction shown in Fig. 12 may be employed. In said figure I have shown a stud 92 projecting into the notched end of a forked lever 93 pivoted at 94 and having an arm 95 connected by a link 96 to an offset portion 97 of an operating lever 60a, corresponding to the lever 60 previously described. A spring 98 acts in addition to gravity to swing the lever 60a downward. 40

With the construction shown in Fig. 12, upward movement of the platen 21 will cause swinging 45 upward movement of the lever 60a, thus feeding the ribbon as previously described.

In Fig. 13 I have shown a further modification of my invention in which feed pawls 100 and 101 are pivoted at 102 and 103 on an operating lever 50 104 pivoted at 105 on a supporting bracket 106.

Flat plates or knife blades 107 and 108 are mounted to rock in notches 109 and 110 in a plate 111 which is secured to the operating lever 104 by spacing studs 112. 55

The upper edge of the upper flat plate or knife blade 107 is received in a slot 113 in the lower side of a link 114 which connects the upper ends of the feed pawls 100 and 101. The lower edge of the lower blade 108 extends into a similar slot in the upper edge of a link 115, the ends of which are connected to arms 116 and 117 which in turn are connected to crank levers 118 and 119, as in the form previously described. A spring 119a connects intermediate points 121 and 122 of the 60 blades 107 and 108 and is movable behind the plate 111. A second spring 119b gives the return movement to the lever 104. 65

The parts are shown in Fig. 13 immediately after a ribbon shift and as the feed to the right-hand spool S is about to begin. As the ribbon roll on the spool S increases, the link 115 will be moved to the right in Fig. 13 until the center line of the spring 119a is at the right of the plane of the blade 107. The blade 107 will then swing 70 75

over to the right with a snap action, carrying with it the link 114, disengaging the feed pawl 101 and at the same time rendering the feed pawl 100 operative.

5 When the left-hand spool S' is again filled, the parts will return to the position shown in Fig. 13, with the right-hand feed pawl 101 operative.

In the further modification shown in Fig. 14, feed pawls 120 and 121^a are pivoted at 122^a and 123 on an operating lever 124 which swings about a fixed pivot stud 125. The feed pawls 120 and 121^a alternately engage ratchet wheels 45 and 46 previously described, and are connected at their upper ends by a tension spring 126.

15 A swivel plate 127 is also pivoted on the stud 125 and is provided with lugs 128 and 129 positioned for alternate engagement by toothed shift arms 130 and 131, associated with crank levers 132 and 133 which engage the ribbon rolls. The shift arms 130 and 131 are preferably connected by a spring 135.

20 The plate 127 also has portions engageable with the upper ends of the feed pawls 120 and 121^a and rendering them alternately inoperative. A spring 25 137 gives the lever its return movement.

25 When a spool is filled as indicated at the right in Fig. 14, the corresponding shift arm 131 will swing up into the path of the lug 129. The arms 130 and 131 have curved upper edges which are 30 provided with a plurality of teeth 140 to engage the lugs 128 or 129.

35 When the operating lever 124 swings upward with the shift arm 131 in position to engage the lug 129, such upward movement will cause angular movement of the swivel plate 127 relative to the lever 124, thus rendering the pawl 121^a inoperative and releasing the pawl 120. Preferably the relative movement at each actuation accomplishes a partial shift only of the swivel plate, so 40 that complete disengagement of one feed pawl and engagement of the other requires two or three operations of the lever 124, thus distributing the load on successive operations of the solenoid and platen.

45 Having thus described my invention and the advantages thereof, I do not wish to be limited to the details herein disclosed, otherwise than as set forth in the claims, but what I claim is:—

1. Ribbon mechanism for recording apparatus 50 comprising ribbon spools rotatable about spaced axes and provided with ratchet wheels, a movable operating member, a power-actuated platen effective to move said member in a non-feeding direction only, a spring to give said member a feeding movement only, feed pawls pivotally mounted on said member and alternately engaging said ratchet wheels, and automatic means to render one of said pawls operative and the other pawl inoperative alternately.

60 2. Ribbon mechanism for recording apparatus comprising ribbon spools rotatable about spaced axes and provided with ratchet wheels, a movable operating member, a power-actuated platen effective to move said member in a non-feeding direction only, a spring to give said member a feeding movement only, feed pawls pivotally mounted on said member and alternately engaging said ratchet wheels, and automatic means to render one of said pawls operative and the other pawl inoperative alternately, said latter means being actuated through movement of said member by said platen and being controlled by increase in diameter of one ribbon spool and simultaneous decrease in diameter of the other ribbon spool.

3. Ribbon mechanism for recording apparatus comprising ribbon spools rotatable about spaced axes and provided with ratchet wheels, a movable operating member, a power-actuated platen effective to move said member in one direction, means to move said member in the opposite direction, feed pawls pivotally mounted on said member and alternately engaging said ratchet wheels, automatic means to render one of said pawls operative and the other pawl inoperative alternately, said latter means being actuated through movement of said member by said platen, and ribbon-controlled devices to initiate reversal of ribbon feed by said automatic means.

4. Ribbon mechanism for recording apparatus 15 comprising ribbon spools rotatable about spaced axes and provided with ratchet wheels, a movable operating member, a power-actuated platen effective to move said member in one direction, means to move said member in the opposite direction, feed pawls pivotally mounted on said member and alternately engaging said ratchet wheels, a locking lever shiftable to render one 20 of said pawls operative and the other inoperative alternately, and ribbon-controlled devices to initiate shifting movement of said locking lever.

5. Ribbon mechanism for recording apparatus comprising ribbon spools rotatable about spaced axes and provided with ratchet wheels, a movable operating member, a power-actuated platen 30 effective to move said member in one direction, means to move said member in the opposite direction, feed pawls pivotally mounted on said member and alternately engaging said ratchet wheels, a locking lever mounted on said movable 35 member and shiftable to render one of said pawls operative and the other inoperative alternately, and ribbon-controlled devices mounted on fixed structure and alternately engaging with said locking member to effect shifting thereof.

40 6. Ribbon mechanism for recording apparatus comprising ribbon spools rotatable about spaced axes and provided with ratchet wheels, a movable operating member, a power-actuated platen effective to move said member in one direction, 45 feed pawls pivotally mounted on said member and alternately engaging said ratchet wheels, a locking lever mounted on said movable member and shiftable to render one of said pawls operative and the other inoperative alternately, and ribbon-controlled devices mounted on fixed structure 50 and alternately engaging with said locking member to effect shifting thereof, said latter devices being each movable toward operative position by increase in diameter of the associated 55 ribbon roll.

7. Ribbon mechanism for recording apparatus comprising ribbon spools mounted to rotate about spaced axes, feeding means for said spools, means to reverse said feeding means, power 60 means to effect an impression on said recording apparatus, and connections through which said power means actuates said reversing means on its power stroke and simultaneously gives said feeding means an idle return movement.

65 8. In a ribbon mechanism, a pair of ribbon spools mounted to rotate about spaced axes and provided with ratchet wheels, feed pawls for said wheels, a lock lever shiftable to render either pawl operative and the other inoperative alternately, and ribbon-controlled means to effect shifting said lock lever, said ribbon-controlled means comprising a pair of toothed levers alternately engaging the lock lever, and in which a part associated with each toothed lever engages 70 75

the roll of ribbon on one of said spools to detect ribbon exhaustion and initiate ribbon reversal.

9. In a ribbon mechanism, a pair of ribbon spools mounted to rotate about spaced axes and provided with ratchet wheels, feed pawls for said wheels, a lock lever shiftable to render either pawl operative and the other inoperative alternately, and ribbon-controlled means to effect shifting of said lock lever, said ribbon-controlled means comprising a pair of toothed levers alternately engaging the lock lever, and in which a crank lever is associated with each toothed lever and directly engages the roll of ribbon on one side of said spools to detect ribbon exhaustion and initiate ribbon reversal.

10. Ribbon mechanism for recording apparatus comprising ribbon spools rotatable about spaced axes and provided with ratchet wheels, a movable operating member, a power-actuated platen effective to move said member in one direction, means to move said member in the opposite direction, feed pawls pivotally mounted on said member and alternately engaging said ratchet wheels, and automatic means to render

one of said pawls operative and the other pawl inoperative alternately, said platen having an extension directly engaging and lifting said movable member.

11. Ribbon mechanism for recording apparatus comprising ribbon spools mounted on spaced axes and provided with ratchet wheels, a pivoted operating lever, feed pawls on said lever for said spools, a plate swiveled about the axis of said lever, power means to rock said plate and to thereby render said feed pawls alternately operative and inoperative, and devices controlling the movements of said swiveled plate and responsive to changes in ribbon spool diameter.

12. Ribbon mechanism for recording apparatus comprising ribbon spools mounted on spaced axes and provided with ratchet wheels, a pivoted operating lever, feed pawls on said lever for said spools, a plate swiveled about the axis of said lever, and ribbon-controlled means operating to rock said plate by a series of cumulative partial steps and to thereby render said feed pawls alternately operative and inoperative.

ALFRED RUTTIMAN.
